[57] CLAIM

I claim the ornamental design for a golf bag lighter, as shown and described.

DESCRIPTION

FIG. 1 is a left side view of my new design.

FIG. 2 is a left side perspective view of my new design showing the lighter in operation.

FIG. 3 is a front view of my new design.

FIG. 4 is a right side view of my new design.

FIG. 5 is a rear view of my new design.

FIG. 6 is a top plan view of my new design; and,

FIG. 7 is a bottom plan view of my new design.

The broken lines are shown for illustrative purposes only and form no part of the claimed design.
